Primary Examiner—Robert Peshock

ABSTRACT: A claspless partial denture having an elongated resilient member or cantilever spring in substantially L-shaped form in which the horizontal portion is affixed to the saddle beneath an end tooth and the vertical portion extends along said end tooth but is not connected thereto. The horizontal portion of the spring carries a male member which telescopingly interlocks in a female slot or channel member in the crown abutment which opens through the occlusal and gingival surfaces thereof and has a reduced throat which opens through one vertical face thereof, either the distal or mesial face, depending on the position of attachment of the partial denture. A bracing arm is carried by a strut of the saddle to one side of but unconnected to the vertical portion of the cantilever spring, the bracing arm being adapted to engage the crown abutment. The denture is adjustable, self-cleaning and absorbs displacement stresses.

CLASPLESS PARTIAL DENTURE AXIAL RETAINER CONSTRUCTION

This invention relates to removable partial denture constructions and constitutes an improvement over my U.S. Pat. No. 3,228,106.

In said patent, a resilient axial member or cantilever spring is provided which is substantially L-shaped, the horizontal portion of which is affixed to the saddle of the denture. The saddle includes an integral sleeve portion 50 which opposes the crowned abutment tooth and the vertical portion of the spring extends vertically along the abutment surface of the sleeve portion but is free to move relative thereto. The crowned abutment tooth is provided with an axial channel into which the vertical portion of the spring fits but in which it is not retained. The denture is actually retained on the abutment tooth by an arcuate clasp having integral axial struts which are received in complementary channels in the crowned abutment tooth, preferably 180° apart. The lower edge of the clasp is adapted to abut a lingual shoulder on the crowned abutment tooth to resist displacement of the denture toward the gingiva.

While the patented device effectively serves to absorb lateral stresses and any wear between the denture and the abutment tooth can be compensated by bending the cantilever spring, nevertheless the denture construction requires the use of a clasp with struts that engage in complementary grooves in the crowned abutment tooth for retention and cannot be tissue bearing in view of the engagement of the lower edge of the clasp with the lingual abutment shoulder.

The primary object of the invention is to provide a clasless axial retention system which incorporates the desirable stress-absorbing and adjustment features of the patented structure but simplifies its construction, manufacture and assembly.

An important object of the invention is to provide an axial denture retainer in which the vertical portion of the L-shaped cantilever spring, as above described, is removably retained in a slot member which extends the full height of the crowned abutment tooth thus eliminating the need for a clasp with struts to engage in grooves in the abutment without sacrificing the stress-absorbing and adjustment features of the spring.

Another object of the invention is to provide an axial partial denture retainer of the character described wherein the denture may be wholly tissue bearing to eliminate rotation around the abutment tooth and thus eliminate stresses thereon. The instant device may, of course, also be nontissue bearing, if desired.

Another object of the invention is to provide a partial denture construction incorporating a cantilever spring which is affixed to the saddle of the denture and includes a vertical portion having a male or flange member which is removably retained in a female slot member in the abutment tooth, the latter running the full height of the abutment tooth and open top and bottom thus rendering the device self-cleaning.

Another object of the invention is to provide a partial denture construction incorporating a cantilever spring which is affixed to the saddle of the denture and includes a vertical portion having a male or flange member which is removably retained in a female slot member in the abutment tooth in combination with a bracing arm which engages but is not locked to the abutment tooth thus simplifying the procedure for adjusting the denture when the male member becomes loose in the female or slot member, since all that is required is the movement of the vertical portion or male member of the spring laterally toward the back of the slot member and tightening the bracing arm.

These and other objects of the invention will become apparent as the following description proceeds in conjunction with the accompanying drawings, wherein:

FIG. 1 is a fragmentary view of the human maxilla projected upon the occlusal plane and illustrating the present removable denture construction in place, ready for use;

FIG. 2 is an enlarged view of the area designated 2 in the circular arrow on FIG. 1;

FIG. 3 is a sectional view taken on the line 3-3 of FIG. 2;

FIG. 4 is a view similar to FIG. 3 showing the denture disengaged from the abutment tooth but in position for engagement;

FIG. 5 is a sectional view taken on the line 5-5 of FIG. 4;

FIG. 6 is an exploded perspective view of the male and female members of the invention; and

FIGS. 7-9 are profiles of alternative modifications of the male and female members.

Specific reference is now made to the drawings in which similar reference characters are used for corresponding elements throughout. The present partial denture 10 is removably mounted in the mandible 12 which may consist of natural or capped teeth 14, two of which 16 are abutment teeth which are suitably crowned as at 18. It is understood that while a particular type of partial denture is herein shown, the same is merely illustrative and the principles of the invention are applicable to all types of partial dentures. Thus, for example, the partial denture can fill in the space between a crowned molar serving as one abutment tooth and a crowned incisor serving as the other abutment tooth, etc.

The denture is formed in a conventional manner and may be molded entirely of a suitable plastic, such as acrylic, in which artificial teeth are mounted or it may preferably be formed of a metal saddle 20 with plastic 22 molded thereto in which the artificial teeth 24 are mounted. Those artificial teeth which oppose the abutment teeth 16 are designated 26.

A resilient member or cantilever spring 28 is provided which includes a metallic rod or wire bent into substantially L-shaped form to produce a generally horizontal portion 30, a generally vertical portion 32 and an arcuate corner 34 joining them. The rod or wire may be solid or tubular and made of corrosion-resistant spring metal. Preferably, the rod or wire is solid and of circular or oval cross section and comprises platinum with a high palladium content.

Integral with or otherwise rigidly affixed to the vertical portion 32 of the cantilever spring or wire and substantially coextensive therewith is a male member 36 forming at the juncture with the wire a reduced neck portion 38 of width less than the diameter of the wire. The neck is in turn integral with or affixed to a flange member 40, see FIGS. 1-6, having flange portions 42 extending beyond the wire on both sides thereof, the rear face 44 of the flange member being flat.

The metallic saddle 20 is formed with an upright strut 46 which extends to one side of the artificial tooth 26 and carries at its upper end a curved bracing arm 48 which is adapted to embrace the abutment tooth 16 as shown in FIGS. 1-3, the bracing arm including also an arcuate portion 50 which is received in a suitable recess or groove 52 which is provided in a face portion of the artificial tooth 26.

The horizontal portion 30 of the cantilever spring 28 is affixed, as by soldering or welding, to the upper surface of the metallic saddle 20, as seen in FIGS. 3 and 4, beneath the artificial tooth 26 in such a manner that the curved corner 34 thereof extends outside of the saddle at the strut 46 while the vertical portion 32 extends the full height of the tooth 26 with the portion 36 bearing against the portion 50 of the bracing arm which in turn is received in the recess 52 in the tooth 26.

A female member 54 is provided in the form of a metallic or plastic channel or slot member which is complementary to and coextensive with the male or flange member 36. Accordingly, it includes a rear substantially flat wall 56, substantially perpendicular sidewalls 58 and short front walls 60 which terminate in a throat 62 only slightly wider than the width of the neck 38 of the male member and opening through a vertical face, distal or mesial, of the crown abutment depending upon where the partial denture is attached. Thus a vertical channel 64 is formed which is open at the top through the occlusal surface 65 of the crown abutment and at the bottom through the gingival surface 66 of the crown abutment. The front walls 60 are continued into short outwardly flaring or divergent lips 67.

When the crown 18 of the abutment tooth is still in its wax-up form, the female member is positioned therein to extend the full height of the tooth at the posterior or anterior surface

thereof, whichever is to face the opposed artificial tooth containing the male member 28. The wax form is then cast in a manner well known to the art to form the crown with the female slot member 54 integral purposes. It is to be understood that the female slot member is shown in FIGS. 3-5 as a separate member with crosshatching different from the crown 18 only for illustrative purposes. In actuality, the crown will be of one consistency and the female member will appear therein as a vertical channel 64, open at its top and bottom ends and having inner walls corresponding to the rear wall 56, the sidewalls 58, the front walls 60 and a flared opening corresponding to the lips 66 leading to a throat 62, see FIG. 2.

In use, the partial denture 10 is removably mounted in the mandible by inserting each male flange member 28 associated with each artificial tooth 26 in each female slot member 54 associated with each abutment tooth 16 through the open top thereof until the lower edge of the bracing arm is adjacent the gingiva and the denture is properly seated on the gums. In this position the bracing arm embraces the abutment tooth as shown in FIGS. 1 and 2. Thus the cantilever spring 28 renders the denture flexibly adjustable to displacement yet it coacts with the female slot member to supply the retentive function. Because this is accomplished between the interlocking, telescoping action between the male and female members, the denture can be entirely tissue bearing, so that rotation around the natural crowned abutment tooth and stresses thereon are minimized if not entirely eliminated. Since the female member is entirely open, top and bottom, through the occlusal and gingival surfaces of the crown abutment, it is also self-cleaning. Excessive frictional wear due to rigidity, tissue resorption, lateral and occlusal stresses are thus substantially reduced.

In the event that the male members should become loose in the female member as a result of excessive wear and stresses, adjustment can be readily effected by moving the male member 28 towards the rear wall 56 of the female member 54 and if additional adjustment is required, the bracing arm can also be tightened. This can be contrasted with the Stern denture attachment shown and described in U.S. Pat. No. 1,641,557. In that structure, a box socket is fixed in the abutment tooth and a substantially T-shaped shank is fixed to the bridge which fits into the box socket, the latter being closed at its bottom end. Since there is no cantilever spring attached to the T-shaped shank of Stern, it cannot function to absorb stresses and when the shank becomes loose in the box socket, which is often because of the rigidity of the structure, it can only be adjusted by wedging the shank to spread it, which is substantially a one-time permanent operation.

While the drawings show a tissue bearing partial denture, it will be understood that it can also be nontissue bearing by providing a shoulder at the gingival edge of the crown of the abutment tooth 16 against which the lower edge of the bracing arm can bear. In addition, although it is preferred that the horizontal portion 30 of the cantilever spring be soldered or welded to a metal saddle, it can also be embedded in a wholly plastic saddle, in which case the horizontal portion 30 is formed with a loop. Also, while the flange member 36 functions best with two flanges 42 on both sides of the vertical portion 32 of the cantilever spring, one such flange can also be used, in which case the profile of the channel 64 of the female slot member 54 will be made to correspond thereto.

FIGS. 7-9 illustrate variants of the flange members which can be made integral with or otherwise fixedly secured to the vertical portion 32 of the cantilever spring and corresponding female socket members used to form corresponding channels in the abutment tooth crown.

Thus in the modification of FIG. 7, the male member 68 is generally ovoidal in horizontal cross section and includes transverse portions 70 which extend laterally beyond the diameter of the portion 32 and is joined thereto by a reduced neck 72. The female socket member 74 corresponds in contour to the male member 70 and has front edges forming a throat 76 corresponding to the neck 72, there being oppositely extending lips 78 at the throat.

In the modification of FIG. 8, the male member 80 is substantially dovetail in horizontal cross section and includes inwardly inclined sidewalls 82 which converge to form a reduced neck 84 joining the vertical portion 32 of the cantilever. Corner portions 86 of the male member 80, where the side portions 82 thereof join the rear wall 88, extend laterally beyond the diameter of the portion 32. The female socket member 90 is also dovetail in horizontal cross section and corresponds to the male member 80 forming at its converging front ends a throat 92 receiving the neck 84, there being lips 94 extending in opposite directions from the throat.

In the modification shown in FIG. 9, the male member 96 is substantially circular in horizontal cross section and of diameter substantially the same as that of the portion 32, the male member 96 being joined to the portion 32 by a reduced neck 98. The female socket member 100 is also substantially circular in horizontal cross section and corresponds to the male member 96, the female socket forming at its front end a reduced throat 102 receiving the neck 98, there being lips 104 which extend in opposite directions from the throat.

The use of partial dentures equipped with the modified male and female members shown in FIGS. 7-9 is the same as that described hereinbefore with reference to the form shown in the remaining figures. It will be understood that the instant construction is used wherever the adjacent tooth of the partial denture is to be attached to the crown abutment. It should also be noted that the cantilever spring 28 serves the dual function of a structural member and a means to absorb transverse vibrations. The spring 28 is a bar or rod of uniform cross section so that the stress distribution thereacross will be uniform when a load is applied axially thereto.

While preferred embodiments of the invention have here been shown and described, it will be understood that skilled artisans may make minor variations without departing from the spirit of the invention.

I claim:

1. In a removable clasless partial denture construction, a crowned abutment and a partial denture including a saddle, an elongated resilient member having a generally horizontal portion affixed to said saddle and a generally vertical portion extending outside of said saddle and unconnected thereto, a male member carried by said vertical portion and a generally vertical female member in said crowned abutment opening top and bottom through the occlusal and gingival surfaces of the crown and through one vertical face thereof, removably, telescoping and locking retaining said male member therein, said male and female members being unrestricted so as to make the saddle seat on the tissue-bearing surface of the gum.
2. The denture of claim 1 wherein said resilient member is a substantially L-shaped rod.
3. The denture of claim 1 in which said saddle includes a vertical strut behind and unconnected to said vertical portion of said resilient member, and an arcuate bracing arm at the upper end of said strut adapted to engage said abutment without connection thereto when said male and female members are interlocked.
4. The denture of claim 2 wherein said male member is a flange and said female member corresponds in horizontal cross section to that of said male member so that said male and female members closely interfit.
5. The denture of claim 4 wherein said flange extends beyond the diameter of said resilient rod and is connected to said rod by a reduced neck portion, the corresponding female member including a reduced throat opening through a vertical face of said abutment and embracing said neck portion.
6. The denture of claim 4 wherein said flange is of dovetail cross section and extends beyond the diameter of said resilient rod and is connected to said rod by a reduced neck portion, the corresponding female member including a reduced throat opening through a vertical face of said abutment and embracing said neck portion.

7. The denture of claim 4 wherein said flange is of generally ovular cross section and extends beyond the diameter of said resilient rod and is connected to said rod by a reduced neck portion, the corresponding female member including a reduced throat opening through a vertical face of said abutment and embracing said neck portion.

8. The denture of claim 1 wherein said resilient member is a substantially L-shaped rod and said male member is a rod connected to the vertical portion thereof by a reduced neck portion, said female member corresponding in horizontal cross section to said male member rod and including a reduced throat opening through a vertical face of said abutment and embracing said neck portion when said male and female members telescopingly interlock.

9. A removable claspless partial denture comprising a saddle and artificial teeth, a substantially L-shaped spring rod having a horizontal portion affixed to said saddle and a verti-

cal portion extending along one end tooth but unconnected thereto, a male member connected to said vertical portion by means of a reduced neck, said male member being adapted to telescopingly interlock with a female slot member in a crown abutment, a strut carried by said saddle to one side of but unconnected to said vertical portion of said rod and an arcuate bracing arm at the top of said strut.

10. The denture of claim 9 wherein said male member is a flange member extending beyond the diameter of said vertical portion of said rod.

11. The denture of claim 10 wherein said male member is of generally dovetail, horizontal cross section.

12. The denture of claim 10 wherein said male member is of generally ovular, horizontal cross section.

15 13. The denture of claim 9 wherein said male member is of generally circular, horizontal cross section.
